UNITED STATES PATENT OFFICE

RICHARD HOWLAND RANGER, OF NEWARK, NEW JERSEY, ASSIGNOR TO RADIO CORPORATION OF AMERICA, A CORPORATION OF DELAWARE

FACSIMILE TRANSMISSION

Application filed May 3, 1929. Serial No. 360,063.

The present invention relates particularly to facsimile transmission and reproduction, and is particularly directed to an alarm system whereby it is possible to indicate the time 5 when a picture which has been transmitted or received is completed so that an operator may attend to the machine for recording and either stop its motion or insert a new picture for transmission or a new record surface for 10 reproduction and thus avoid considerable waste of time in transmission, and avoid the need of constantly watching the reproduction and transmission to determine the time length of operation.

More particularly, the invention is directed 15 to an alarm system whereby it is possible to provide an arrangement which will automatically turn off the transmitter or receiver at the time when a picture has been transmitted.

Therefore, as a primary object of my invention, I have sought to develop a method and means by which the time when a picture 20 has been recorded will be indicated.

Still a further object of my invention has 25 been to provide a system wherein each successive line of reproduction of the picture will determine the time of indication of the alarm means and the time of turning off either or both the transmitter and receiver.

Still a further object of my invention is to 30 provide an alarm system for indicating the end of the time required for transmitting and receiving the picture which is not directly dependent upon any time element but which, 35 on the other hand, is determined by the amount of detail desired in a transmitted and received picture.

Still other objects of my invention are to provide in a manner to be hereinafter set 40 forth an arrangement for indicating the time when a single transmission and reception of a picture has been completed which is relatively simple in its construction and arrangement of parts, a system which is cheap and 45 convenient to install, a system which is highly efficient in its use, readily operated, easily set up, and which can be used in conjunction with substantially all known types of transmitting and receiving apparatus for facsimile 50 developments.

Still other and ancillary objects of my invention will become apparent and at once suggest themselves to those skilled in the art to which the invention relates by making reference to the accompanying drawings forming, together with the following specification and claims, a part of my disclosure. 55

By Fig. 1 of the drawings, I have illustrated in a conventional manner an alarm system as applied to either a facsimile transmitting or receiving machine; and, 60

By Fig. 2, I have diagrammatically illustrated a suitable arrangement for wiring an electrical system for indicating the time when a single transmission of a picture and the like 65 ends.

In conjunction with the present disclosure, reference may be had to my copending application, Serial No. 360,064, filed May 3, 1929, disclosing a preferred type of transmitting or receiving apparatus with which the present invention may be associated. 70

Now referring particularly to Fig. 1 of the drawings, I have provided a cylinder or drum 1 upon which a record surface for transmission, or a light or heat sensitive record for receiving a picture may be mounted. As shown, the drum 1 is arranged to turn in the direction shown by the arrow thereon and may be driven by means of a drive gear 3 75 carried upon a shaft 5 and turned through means of a worm gear 7 mounted and carried by a spindle 9 which derives rotational movement in the manner set forth in the above referred to copending application. The 80 spindle 9 is preferably mounted from brackets or other bearing surfaces 11 carried upon an end frame work 13 for supporting the drum surface 1. As has been shown, the end of the shaft 5 is provided with a knurled 85 thumb nut 15 so that the drum surface 1 may be easily turned in the direction of the arrow by simply turning the nut so that it may be positioned at the proper point for starting the picture without the need of turning the 90 drive shaft 9. 95

In order to prevent a backward motion of the drum 1 in the opposite direction from that shown for driving the same, I have provided a ratchet wheel 17 and a spring 100

mounted pawl 19 for engaging therewith. Mounted behind the main drive gear 3 carried by the shaft 5 for rotating the drum, I have provided a disk member 21 which is frictionally carried upon the shaft 5 so as to engage with the gear 3 and to be rotated thereby in a corresponding direction. As will be seen particularly in conjunction with Fig. 2 of the drawings, where the disk 21 has been shown at a point substantially near the end of transmission, in contrast to the position shown by Fig. 1 wherein the disk is either at the beginning or at the end of transmission, I have provided in the disk surface 21 a notch 23 into which may engage a stop member 25 pivoted at a central point thereof 27 and arranged to form the armature of a pair of relays 29 and 31 respectively. It will be seen that, where the relay 31 is energized, the arm 25 provided with the forked end 33 will be turned in a clock-wise direction as shown about the point of support 27 as a pivot and when the disk 21 is in the position as shown by Fig. 1 that the forked projection 33 on the arm 25 will engage in the slot 23 of the disk and hold the same in such position. At such periods of time, the disk 23 will slip with respect to the drive gear 3, since the friction from the drive gear upon the disk surface is not sufficient to pull the same in a clock-wise manner when the forked end of the armature 25 engages in the slot 23, so that the armature may not be pulled out of the slot.

Now particularly referring to the operation of the arrangement, it may be seen by making reference to my copending application, Serial No. 360,064, filed May 3, 1929, that at each period of time when a supporting carriage moving back and forth upon an endless spiral track reaches one end of its motion that it will close a contact arm 35 so as to cause the same to press against the contact point 37. The arm 35 is preferably connected at a terminal 39 with a negative point on the source of potential so that as the contact arm 35 moves over against the contact point 37 current will tend to flow. Therefore, for a starting position of the transmitting or receiving machine, the switch 39 may be thrown upon the contact 41 so that current will then flow from the point of connection 39 through the contact arm 35, the point of connection 37 through the switch arm 39, the contact 41, the conductor 45, to the relay coil 29, which has one end thereof connected with the conductor 45 and the other end connected to a terminal point 47 to which positive potential from the same potential source connected at 39 is connected. Thus, the relay 29 is energized and the armature 25 moved in a counter clock-wise direction about the point 27 as a pivot so that the forked projection 33 thereon is withdrawn from the slotted member 23. The disk 21 is now free to rotate in a clock-wise direction in accord-

ance with rotational movement derived from the rotation of the shaft 9.

Immediately upon starting the drum 1 rotating by means of the drive shaft 9, and at the time when the transmission of the picture has been started by releasing the armature 25 from the slot 23, the switch arm 39 is thrown over upon a second contact point 43 so that current may then flow from the point of connection 39 of the negative source of potential through the contact arm 35 through the point of connection 37 through the switch arm 39, the contact point 43, the conductor 49 to the relay coil 31, from whence it flows to the point of connection 47 of the positive source of potential. It will thus be seen, as the carriage carrying either the analyzing system for analyzing the picture in the case of transmission, or the light responsive elements or heat responsive elements in the case of reception, longitudinally traverses the recording drum 1 so as to project either light or heat upon the record surface carried by the drum surface, that at each end of the longitudinal stroke of the said scanning or reproducing system, the contact arm 35 is closed against the contact point 37 and with the switch arm 39 connected to contact 43 of the switch that the relay coil 31 will be energized at each end of the stroke or at each time the analyzing or reproducing system has been moved longitudinally with respect to the drum. Thus, the armature 25 pivoted about the contact point 27 is moved in a clock-wise direction about the pivot point towards the relay coil 31 and tends to rest against the contact 51 so as to form a connection from a source of potential having its positive terminal connected to the point of pivotal support 27 of the armature 25 so that it may flow through the armature 25 to the contact point 51 or to the contact point 53. However, after the picture carrying drum 1 has once started to rotate, it may be readily seen, in case the picture is to be analyzed or reproduced in a diagonal manner, as shown and described in connection with my copending application above referred to, Serial No. 360,064, filed May 3, 1929, that for each longitudinal movement of the analyzing or reproducing carriage with respect to the drum 1 that the drum has turned slightly more than a single revolution or in conjunction with analyzing or reproducing in a longitudinal direction with respect to the drum 1, as shown in the last named copending application, with the drum being advanced at the end of each stroke a line advance equal to the width of a single line of analyzing, or reproducing, or a plurality of lines of analyzing and reproducing in case of multiplex transmission, that it will be necessary to entirely complete the transmission and reception of the picture image in order to effect the recurrence of the

combination that the slot in the disk member 21 frictionally driven by means of the gear member 3 is opposite the forked projection 33 at exactly the same instant that the scanning or reproducing system completes a horizontal stroke.

Thus, in either case, and irrespective of the type of analyzing or reproducing, it may readily be seen that it will only be at such a time when a complete picture has been transmitted and received that the relay coil 31 will be energized at a time exactly corresponding to the time when the slot 23 on the disk member 21 is in such a position that the forked end 23 of the armature 25 may rest therein. Thus, the armature 25 will never rest against the contact 51 except at times when the picture has been completely transmitted, so that the drum has either made a plurality of revolutions with an overlapping beyond a single complete revolution additively totaling another single revolution or when the drum has been rotated through one single revolution in case of parallel line scanning.

Now, supposing that the disk 21 has been turned through either a complete revolution or a plurality of revolutions having an overlapping totaling a single revolution, the forked projection 33 on the armature 25 will rest in the slot 23 and the armature 25 will come to rest against the contact point 51. At such a time, current which is connected with its positive terminal to the contact or pivotal point 27 of the armature 25 will flow through the contact point 27, the armature 25 through the contact point 51 and the conductor 55, through an alarm system 57 and thence to the transmitter, and, if desired, through a relay system which may turn off the transmitter or receiver so that pictures will no longer be sent or received.

It may be seen, if the alarm system 57 is arranged in the form of a bell and the transmitter has been turned off by reason of the fact that the armature 25 has come to rest on the contact point 51, that the alarm 57 will continue to indicate the end of the transmission. Therefore, if the alarm system 57 be a bell, it will continue to ring, or if it be a light, it will continue to glow, and the operator will observe the indication and know that he must attend the machine and remove the transmitted or finished record therefrom so that another record may be substituted therefor.

At starting position, when the relay 29 is operated by closing the switch arm 39 upon the contact point 41, it will be seen that the armature 25 will come to rest upon the contact point 53, and thus current will flow from the positive source of potential through the contact point 27 pivotally supporting armature 25, through the armature 25 to the contact point 53 and thence to the negative

source of potential so as to control by means of a differentially wound relay or the like the transmitter or receiver so as to turn the same on in contrast to turning either the transmitter or receiver off when the armature rests against the contact point 51.

Other modifications of the arrangement herein disclosed and set forth will at once suggest themselves to those skilled in the art to which the invention relates, and I, therefore, desire to be limited in so far as what modifications and changes I may make to this system only in so far as the spirit and scope of the hereinafter appended claims necessitates.

Having now described my invention, what I claim and desire to secure by Letters Patent is the following:

1. In a system for indicating the completion of the transmission or reception of pictures, a rotatable picture carrying drum for supporting a picture surface, a disk on the end of said drum and rotating therewith, said disk having a notched portion on the periphery thereof, a relay having an armature adapted to rest in the notched portion of said disk member at a predetermined position thereof, means for energizing said relay at predetermined intervals during the period of rotation of said drum, and means provided by the position of said armature when resting in said notched portion for energizing an alarm circuit for indicating the end of a single transmission of a picture.

2. In an alarm system for indicating the completion of the transmission or reception of pictures, a rotatable picture carrying drum for supporting a picture surface, a disk with a single slot therein frictionally driven on the end of said drum, a relay having an armature adapted to rest against said disk member, means for energizing said relay at predetermined intervals during the rotation of said drum and causing said armature to bear against said disk, and means provided by the rotation of said drum and disk for permitting said armature to rest in said disk slot at the completion of a complete transmission and reception of a picture record, an alarm system for indicating the end of a transmission, and means provided by the position of said armature when resting in said slotted portion for energizing said alarm circuit.

3. In an alarm system for indicating the completion of the transmission or reception of a picture, a rotary picture carrying drum supporting a surface corresponding to a transmitted or received picture, a disk carried on the end of said drum and rotating therewith, said disk having a notch in the periphery thereof, a relay having an armature adapted to rest in the notched portion of said disk member at the point of starting and ending a single transmission, means for energizing said relay at predetermined periods of

time during the rotation of said picture carrying drum, an alarm system, and means provided by the position of said armature when resting in said slotted portion for energizing said alarm circuit and thereby indicating the end of a single transmission of a picture.

4. In a system for transmitting or receiving pictures, a picture carrying drum for supporting a picture for transmission or reception, a disk having a notched portion about the periphery carried on the end of said drum, a relay having an armature adapted to rest in the notched portion of said disk member at the time of starting or ending said transmission, means for energizing said relay at each longitudinal movement of a scanning system with respect to said drum, means for rotating said drum, and means provided by the rotation of said drum for frictionally carrying said disk therewith, and means provided by the energization of said relay for moving said armature against said disk, means provided by said single slot in said disk for permitting said armature to rest in the notched portion of said disk only at the beginning and then at the end of a complete transmission of the picture carried by said drum, and means provided by the position of said armature when resting in said slotted portion for energizing an alarm circuit for indicating the end of a single transmission of a picture.

5. In a system for indicating the completion of the transmission or reception of pictures, a rotatable picture carrying drum, a disk provided with a notch about the periphery thereof mounted for rotational movement with said drum, and a relay and armature means cooperating with said disk whereby upon energization of said relay at predetermined periods during the rotation of said drum said armature is adapted to rest in said notched portion of said disk at the end of a complete picture transmission to indicate the end of transmission and reception.

6. A system for indicating the completion of a transmission of a picture which includes a picture carrying element having a disk mounted on one end thereof for simultaneous movement therewith, said disk being provided with a single slot about the periphery thereof, and an armature and relay means cooperating with said disk and slotted portion thereof for causing an indication of the completion of the picture during time periods when said armature rests in the slotted portion on said disk.

RICHARD HOWLAND RANGER.
